UNITED STATES PATENT OFFICE.

ALEXANDER J. WINDMAYER, OF FORT MADISON, IOWA.

DESIGN FOR A PEDESTAL.

SPECIFICATION forming part of Design No. 21,492, dated April 19, 1892.

Application filed January 27, 1892. Serial No. 419,471. Term of patent 3½ years.

To all whom it may concern:

Be it known that I, ALEXANDER J. WINDMAYER, a citizen of the United States, residing at Fort Madison, in the county of Lee and State 5 of Iowa, have invented and produced a new and original Design for a Pedestal, of which the following is a specification, reference being had to the accompanying drawing, forming part thereof, which represents an elevation of 10 a statue embodying in its pedestal my new design.

The essential feature of the design resides in the treatment of the pedestal, as shown, the same including a base in the form of a 15 column surmounted by a representation of the globe, the latter of which is surrounded at its base by a figure simulating a continuous band of clouds.

The drawing shows the embodiment of the

design in the pedestal of a statue of Columbus, for whom it is intended.

A indicates the column, B the globe, and B' the cloud effects. The globe is disposed so that North America appears in front.

The figure of Columbus (indicated by the 25 letter C) is represented standing and bearing in his right hand an uplifted sword, while the left hand grasps the staff of an unfurled flag; but the figure of Columbus forms no part of the design.

30
I claim—

The design for the pedestal of a statue, herein shown and described.

ALEXANDER J. WINDMAYER.
